CLAIM

I claim the ornamental design for a triangular locket containing a removable and foldable flag, as shown and described.

DESCRIPTION

FIG. 1 is a perspective view of the locket in its preferred embodiment shown opened to allow for removal of the flag present within the body whereby the body and cover are hinged together along the side of the locket. As to the body; all sides are identical and its back is flat and unornamented. FIG. 2 is a perspective view of the locket in its preferred embodiment shown closed.

FIG. 3 is a perspective view of a second embodiment of the locket shown pulled-apart rather than hinged whereby the body and cover are fitted together by friction means. As to the body; all sides are identical and its back is flat and unornamented; and,

FIG. 4 is a perspective view of a third embodiment of the locket shown opened to allow for removal of the flag present within whereby the body and cover are hinged together along the bottom of the locket. As to the body; all sides are identical and its back is flat and unornamented.
